UNITED STATES PATENT OFFICE.

LUCIUS T. GIBBS, OF BROOKLYN, NEW YORK, ASSIGNOR TO THE VEHICLE EQUIPMENT COMPANY, OF SAME PLACE.

RUNNING-GEAR FOR AUTOMOBILES.

SPECIFICATION forming part of Letters Patent No. 670,776, dated March 26, 1901.

Application filed May 25, 1900. Serial No. 17,951. (No model.)

To all whom it may concern:

Be it known that I, LUCIUS T. GIBBS, a citizen of the United States of America, and a resident of the city of New York, borough of Brooklyn, in the State of New York, have invented a new and useful Improvement in Running-Gear for Automobiles, of which the following is a specification.

This invention is additional to my improvement in running-gear for automobiles described and claimed in a previous specification forming part of United States Letters Patent No. 647,600, dated April 17, 1900, relating therewith to automobiles of every description as regards motive power and to the improvement of the same with reference to securing greater flexibility in the running-gear and reducing the strain on the springs and steering-heads. The "pedestal" running-gear set forth in said previous specification comprises vertically-movable pedestal-boxes connected in pairs by the respective axles and pedestals rigidly attached at top to the sills of the vehicle-body and serving to limit the play of said boxes and to transmit driving strains and shocks from wheel and axle directly to said sills.

The present invention consists in a "combination" running-gear comprising pedestals, together with a platform or other type of running-gear, and in certain novel combinations of parts therein, as hereinafter set forth and claimed.

The objects of this invention are to retain all the advantages of the pedestal-gear at one of the axles, and preferably the "driving-axle," where the functions of the pedestal-boxes are most numerous and important, and at the same time to give the other axle (preferably the "steering-axle") a larger adaptation to variety of equipment as regards springs than is practicable in connection with pedestals, to support such other axle by a reach or reaches without connection between the two axles themselves, and to provide for taking up starting and stopping strains and all major shocks at both axles by the single pair of pedestals.

Two sheets of drawings accompany this specification as part thereof.

Figures 1 and 2 of the drawings are side and

top views of the improved running-gear, the inner wheels being removed in the side view and the brake mechanism and the steering devices omitted as forming no part of the present invention. Fig. 3 is a front view, Fig. 4 a side view, and Fig. 5 another front view, illustrating other equipments of the steering-axle; and Fig. 6 is a top view of the steering-axle, showing the form of reach represented in Figs. 4 and 5.

Like letters and numbers refer to like parts in all the figures.

In either form of the improved running-gear as shown in the drawings the driving-axle A is combined with pedestal-boxes B, movable vertically in pedestals C, which are bolted or otherwise rigidly attached at top to the sills of the vehicle-body X and slotted or otherwise adapted to guide such pedestal-boxes and to limit their individual vertical movements, and suitable springs D are interposed between said pedestal-boxes and the bottom of the vehicle-body, and these parts are or may be identical with the corresponding parts described in said previous specification. The steering-axle A' has the customary pair of steering-heads 1 and 2 at its ends and is connected with the vehicle-body by "platform-springs" D' without the interposition of pedestal-boxes or the like, and said steering-axle is connected with the pedestal C by a reach or reaches E.

In the arrangement represented by Figs. 1 and 2 the springs D' are fore-and-aft elliptic springs at the ends of the steering-axle A', and a hinge-joint 3 at the single end of a Y-shaped reach loosely connects the same with the axle A', so as to provide for the independent vertical play of the steering-axle or of the body X, pedestals C, and reach E relatively to the steering-axle. Said single end of the reach E is also loose in the hinge-piece 3 at x, so as to offer no resistance to the independent vertical movements of the respective ends of the steering-axle. The joints 4 between the reach E and pedestals C may be of any kind.

In Fig. 3 a transverse elliptic spring is shown at D', and in Fig. 5 a double spring in the form of a pair of semi-elliptic springs united back to back, illustrating the employ-

ment at this end of the vehicle of any preferred form and arrangement of springs to suit the tastes of different purchasers.

In the arrangement represented by Figs. 4 5 and 6 a pair of reaches E, connected by slip-couplings 5 to the pedestals C, are connected with the steering-axle A' by hinges 3 to provide for independent vertical play, as above.

In either arrangement the driving-axle A 10 and its pedestal-boxes B support the motor or motors M. The wheels W and W' may be of any approved make, and the brake mechanism and steering devices may be those described in said previous specification or of 15 any known or approved construction.

In addition to the modifications above described a fifth-wheel may take the place of the steering-heads, and other like modifications will suggest themselves to those skilled 20 in the art.

Having thus described said improvement, I claim as my invention and desire to patent under this specification—

1. Improved running-gear for an automobile, comprising two pairs of wheels with their axles, without connection between such axles themselves, vertically - movable pedestal-boxes for one axle, springs interposed between said boxes and the bottom of the vehicle-body, 25 a pair of pedestals rigidly attached to the sills of said body, and serving to guide said boxes and to transmit strain and shocks from wheel and axle directly to said sills, springs connecting the other axle with the vehicle- 30 body, without pedestal or the like, and a reach 35

or reaches connecting the axle last named with said pedestals whereby major strains and shocks at both axles are transmitted to said sills of the body by one and the same pair of pedestals.

2. The combination, in running-gear for automobiles, of a driving-axle, pedestal-boxes for said axle, springs interposed between said boxes and the vehicle-body, pedestals rigidly attached to the sills of said body and serving 40 to guide said boxes and to transmit strain and shocks from wheel and axle directly to said sills, a steering-axle, a spring or springs connecting said axle with said body without pedestal or the like, and a reach or reaches connecting 45 said steering-axle and pedestals.

3. The combination, in running-gear for automobiles, of a driving-axle, pedestal-boxes for said axle, springs interposed between said boxes and the vehicle-body, pedestals rigidly 50 attached to the sills of said body and serving to guide said boxes and to transmit strain and shocks from wheel and axle directly to said sills, a steering-axle, a spring or springs connecting said steering-axle with said body 55 without pedestal or the like, and a reach or reaches connecting said steering-axle with said pedestals and having suitable provision for independent vertical play, substantially 60 as hereinbefore specified.

LUCIUS T. GIBBS.
